(57) **CLAIM**

The ornamental design for a bottle kit, as shown and described.

DESCRIPTION

FIG. 1 is a top, side perspective view of a bottle kit in accordance with our new design; and,

FIG. 2 is an exploded side sectional view thereof according to line 2-2 shown in FIG. 1.

The broken lines used to specify the sectional view in FIG. 1 represent unclaimed subject matter and form no part of the claimed design.

1 Claim, 1 Drawing Sheet Fig. 2
